BOWLING BALL RETURN RACK OR THE LIKE

Richard G. Reineman, Covina, Calif., George E. Schaefer, Muskegon Heights, Mich., and George H. Hart, Chicago, Ill., assignors to Brunswick Corporation, a corporation of Delaware

Filed Apr. 15, 1960, Ser. No. 60,203

Term of patent 14 years

(Cl. D34—5)

Fig. 1 is a side elevational view of a bowling ball return rack or the like showing our new design;

Fig. 2 is a top plan view thereof; and

Fig. 3 is a right end elevational view thereof.

The opposite side from that shown in Fig. 1 is substantially identical to that shown.

We claim:

The ornamental design for a bowling ball return rack or the like, as shown and described.
